CLAIM

The ornamental design for a bottom for a dispensing closure, as shown and described.

DESCRIPTION

FIG. 1 is a top perspective view of a bottom for a dispensing closure in accordance with the invention shown with a top lid in the closed position;

FIG. 2 is a front view of the bottom for a dispensing closure from FIG. 1;

FIG. 3 is a back view of the bottom for a dispensing closure from FIG. 1;

FIG. 4 is a right side view of the bottom for a dispensing closure from FIG. 1;

FIG. 5 is a left side view of the bottom for a dispensing closure from FIG. 1;

FIG. 6 is a top view of the bottom for a dispensing closure from FIG. 1;

FIG. 7 is a bottom view of the bottom for a dispensing closure from FIG. 1;

FIG. 8 is a bottom perspective view of the bottom for a dispensing closure from FIG. 1; and,

FIG. 9 is a cross section view of the bottom for a dispensing closure from FIG. 1.

The broken line showing of a lid of the dispensing closure is for the purpose of illustrating portions of the environmental structure and forms no part of the claimed design.
